UNITED STATES PATENT OFFICE

2,550,048.

PHOTOGRAPHIC FILM HANDLING AND
DRYING FRAME

Hugo A. Durst, Los Angeles, Calif.

Application July 20, 1948, Serial No. 39,708

1 Claim. (Cl. 95—100)

1

My invention relates to a frame for receiving and holding photographic films of different sizes while same are being developed, fixed, washed and dried, and the principal objects of my invention are, to provide a simple, efficient and inexpensive frame, especially designed to readily receive and hold films while same are being processed and dried and further, to provide a film holder which may be readily adjusted so as to receive and hold films of different sizes.

A further object of my invention is to provide a film holder which greatly facilitates the proper positioning of the film in the frame and the subsequent removal therefrom.

With the foregoing and other objects in view, my invention consists in certain novel features of construction and arrangement of parts which will be hereinafter more fully described and claimed and illustrated in the accompanying drawing, in which:

Fig. 1 is a plan view of my improved film holder.

Fig. 2 is a cross section taken on the line 2—2 of Fig. 1.

Fig. 3 is an enlarged detail section taken on the line 3—3 of Fig. 1.

Fig. 4 is a cross section taken on the line 4—4 of Fig. 1.

Fig. 5 is a vertical section taken on the line 5—5 of Fig. 1.

Fig. 6 is a cross section taken on the line 6—6 of Fig. 5.

Referring by numerals to the accompanying drawing which illustrates a preferred embodiment of my invention, 10 designates the frame handle consisting of a straight piece of strap metal, provided at its distal end with a hook 11, and pressed in the intermediate portion of the top surface of said handle at predetermined spaced points, are indentations 12.

Rigidly secured to the upper face of handle 10 below hook 11, is one end of a film supporting arm 13, which is L-shaped in cross section and the free end of the upstanding web thereof, projects at right angles over the horizontal web, to form an inverted hook 14.

Rigidly secured on top of the end of arm 13 that is secured to handle 10, is one end of a film clamping member 15 of resilient wire, which overlies the horizontal web 13 and the free end of this member, just beyond hook 14 terminates in a horizontally disposed loop 16.

The central portion of member 15 is bent slightly downward to form a pressure point 17 and formed in the top surface of the horizontal

web of arm 13 below said downwardly bent portion, is a shallow recess 18.

Under normal conditions, or with member 15 disengaged from hook 14, point 17 enters, but does not bear with pressure in recess 18. (see Fig. 3).

Arranged for sliding movement on handle 10, is a plate 19, the side edges 20 of which are bent so as to lie beneath said handle and secured to 10 the underside of said plate is one end of a thin flat spring 21, having a slightly bowed portion 22 which projects a short distance beyond one end of said plate.

Pressed downwardly from the bowed portion of 15 spring 21 near its free end, is a small stud 23, adapted to engage in any one of the indentations 12, handle 10.

Secured on top of plate 19, is one end of an arm 24, identical with arm 13, with the free end 20 of said arm 24 terminating in a hook 25.

Secured on top of the end of arm 24 which is secured to plate 19, is one end of a spring 26, identical with spring 15 and having a loop 27 at its free end and a pressure point 28, near its 25 center for engaging in a recess 29 formed near the center of arm 24.

In the use of my improved film holder, plate 19 is moved lengthwise on handle 10 so as to space the arms 18 and 24 the proper distance apart to 30 receive the film to be processed and said plate will be releasably held in its adjusted position by the engagement of stud 23, in one of the depressions 12, springs 15 and 26 are now disarranged from hooks 14 and 15 and the film is placed in 35 the frame with opposite ends thereof positioned between the horizontal flanges of arms 13 and 24 and said springs.

The free ends of the springs are now pressed down and engaged beneath hooks 14 and 25, 40 thus firmly gripping the central portions of the ends of the film, thereby maintaining same in flat position during processing operations.

After final washing of the film, the frame is suspended by engaging hook over a suitable support during the drying period and if desired, lower spring 26 may be disengaged from hook 25 thus releasing the lower end of the film from the frame to facilitate drainage of water from the 45 lower edge of said film.

Among the advantages to be found in my improved film handling and drying frame are, ease of manipulation and adjustment, the firm gripping and handling of the film in flat position at 50 two points on opposite edges thereof and the fac-

ile manipulation of the film while same is being placed in and removed from the frame.

Thus it will be seen that I have provided a film handling and drying frame that is simple in structure, inexpensive of manufacture and very effective in performing the functions for which it is intended.

Minor changes in the size, form and construction of the various parts on my improved film drying frame may be made and substituted for those herein shown and described, without departing from the spirit of the invention, the scope of which is set forth in the appended claim.

I claim as my invention:

In a film handling and drying frame, a handle comprising a one-piece straight bar of thin material, a hook formed on the distal end of said handle, there being a row of spaced indentations formed in the upper face of said handle, an arm L-shaped in cross section, having one end secured to said handle near said hook and extending at right angles to said handle, a hook on the free end of said arm, a resilient wire spring overlying said arm and having one end secured to the end of the arm which is secured to the handle, the free end of said spring extending beyond the free end of said arm and adapted to engage in the hook on the end thereof, a plate arranged for

5

sliding movement on said handle, a flat spring carried by said plate and having a stud adapted to engage in the indentations in said handle to retain said plate in differently adjusted positions, an arm L-shaped in cross section, having one end secured to said plate and extending at right angles to said handle, a resilient wire spring secured at one end to the end of the arm which is secured to said plate, a hook on the free end of said second mentioned L-shaped arm for receiving and holding the free end of said last mentioned spring and the central portions of both springs being bent downward to form contact points for engaging on top of the central portions of the arms on which they are carried when the free ends of said springs are engaged in the hooks at the free ends of said arms.

HUGO A. DURST.
